UNITED STATES PATENT OFFICE

2,492,434

PROJECTILE QUENCHING APPARATUS

Frank H. Mueller, Decatur, Ill., assignor to
 Mueller Co., Decatur, Ill., a corporation of
 Illinois

Application December 8, 1942, Serial No. 468,281

3 Claims. (Cl. 134—201)

1

This invention relates to method and apparatus for the heat treating of articles of steel. In particular, the invention is concerned with the heat treating of oblong articles, i. e., articles which are longer than broad, to provide zones of different characteristics along the length of the article. Projectiles or shot are a prime example of articles susceptible of treatment in accordance with the invention, and while the apparatus shown in the accompanying drawings is particularly designed for handling this type of article, it will be understood that the invention extends to other articles, such as chisels, bits, and the like, where similar characteristics are desired.

In the case of armor piercing projectiles the head or nose should be extremely hard, whereas the forward part of the body, back about to the band seat, should be characterized not so much by extreme hardness as by toughness, and the base should be relatively soft, but tough. The main object of the invention is to impart these characteristics through simple procedural steps and through the use of apparatus enabling the steps to be carried out with accuracy and ease. How this object is accomplished will be explained with reference to the drawings, in which:

Figure 1 is a plan view of a quenching fixture wherein the projectile is given a primary quench.

Figure 2 is a section on line 2—2 of Figure 1.

Figure 3 is a plan view partly broken away of secondary quenching apparatus wherein a portion of the previously quenched portion of the article is re-quenched.

Figure 4 is a section on line 4—4 of Figure 3.

Figure 5 shows in plan view a detail of the apparatus of Figures 3 and 4.

Figure 6 is a section on line 6—6 of Figure 5, and

Figure 7 is a diagram showing the relationship of the primary and secondary quenching stations to each other, and to a heating station and a receiving station.

Referring first to Figures 1 and 2, the fixture 10 comprises an upright hollow shank portion 11, here shown as integral with an upwardly open bowl portion 12. The shank is in connection with a supply line 13 for a quenching fluid, preferably cold water, and the line is equipped with a valve, not shown, for controlling the water flow. The mixture 10 is preferably disposed in a receptacle adapted to receive overflow.

The bowl chamber or cavity, which is circular in horizontal section, follows generally the vertical contours of the forward portion of a projectile or shot S, disposed therein head down. Three

5 studs 14 threaded through the lower portion of the bowl at equi-distant points are adapted to support the head in the manner indicated in Figure 2. With the projectile resting on the studs in vertical position, it will be noted that the bowl walls are curved substantially as the curve of the projectile head 15 where it joins the cylindrical body 16, the walls diverging somewhat from the projectile above and below this zone. Substantial flow clearance is present all around the projectile. The bowl terminates upwardly in an outwardly flared horizontal flange 17 intermediate the ends of the projectile body, the latter being considered as terminating upwardly at the band seat 18 beyond which is the base 19.

20 A collar or ring 20 has fixed thereto three parallel depending pins or pedestals 21 which are received in vertical bores in flange 17 and are adapted to be locked in adjusted position by means of set screws 22. Collar 20 has a central opening whose diameter is only slightly greater than that of the projectile and is rimmed on its underside by a downwardly projecting annular flange 23 which is merged into the flat underside 24 of the collar on a curve which is like that of the rounded upper lip 24 of the bowl. The upper margin of the collar opening has a 45° bevel which assists in guiding the projectile into the collar opening. The lower face of the collar is spaced above the top edge of the bowl to provide an annular escape passage 26 and the top horizontal face of the collar is below the band seat of the supported projectile.

25 In the use of the fixture, the water is turned on so as to fill the bowl at a rate beyond the discharge capacity of the passage 26 and so that there is a small amount of overflow over the top of collar 20. The heated projectile is dropped into the fixture through the charging opening, 30 splash on the upper part of the projectile being prevented by the collar, the water momentarily surging at an increased rate through the passage 26 as displaced by the entering projectile. Flow now takes place upwardly along the head and forward body portion of the projectile, some going through the collar opening and escaping over the top of the collar so that quenching takes place from the lower end of the projectile back for a length somewhat short of the band seat. 35 From this point up there is no quenching action.

After the quenching action has continued for the desired period, the shot is removed from the fixture 10 and passed to the secondary apparatus 27, Figures 3 to 6.

35 Referring to the last-named figures, reference

numeral 28 designates a pan having a horizontal bottom 29 resting on any suitable framework. The pan has cylindrical sides 30 which terminate upwardly in an angular concave rim portion 31 which is cut away for a distance at 32, Figure 3, down to the cylindrical portion, or to any required extent, to provide an overflow. A block 33 secured on the bottom wall 29 has a concentric opening in which is fixed an upright tubular pedestal 34 on which is rotatable a hub 35. The hub is supported on block 33 through an out-turned portion of a bushing 36.

Extending radially from the hub 35 are a number of arms 37 in the form of flat bars disposed edge up. The outer ends of these arms have secured to their under edges an annular plate 38 which is provided with two concentric series of openings 39 and 40 of less diameter than the body diameter of the shot, the openings of each series being in staggered relation to those of the other and the two series being concentric with the pedestal 34. As shown in Figures 5 and 6, the upper edge of each of the plate openings is beveled and two sets of diametrically opposite offset recesses 46 and 47 are provided. Above each opening 40 is supported an aligned tubular member 41 or 42. The tubular members 41 are welded to the ends of arms 37 while members 42 are supported half way between adjacent members 41 on uprights 43 rising from the plate 38. These uprights also support tubular members 44 which are in alignment with the openings 39 and the members 44 are also welded to the adjacent arms 37 and also to members 41 and 42 if desired, so that a rigid structure is provided.

The lower ends of all the tubular members are spaced equally above plate 38. Their internal diameter is substantially greater than the body diameter of the shot and each member has welded to its upper edge an inwardly overhanging ring 45 whose internal diameter is only slightly greater than the body diameter of the shot, the upper faces of the rings being all in the same horizontal plane. The openings 39 are of a size to receive a part of the head of an inverted shot and, when so received, the upper end of the body will be within the ring 45, as shown in Figure 6, so that the shot will be maintained vertical.

Disposed on the bottom of the pan are a pair of circular pipes 48 and 49 which directly underlie the openings 39 and 40 respectively. Water supply lines 50 and 51 are led up through the bottom of the pan to pipes 48 and 49 and the latter are each provided with top perforations as at 48' and 49' through which the water is delivered to the pan to overflow at 32. The overflow is at such a height that when a shot is supported on the table as in Figure 6, only its head portion will be immersed and consequently the cooling action is limited to this portion of the shot.

A ring 53 fixed to the top of pedestal 34 has fixed thereto a radially extending tubular member 54 in which is slidably a square bar 55 which carries on a vertical axis a roller 56. The roller is urged against members 44 by a spring 57 and normally engages between two of the said members, as shown in Figure 3. This detent mechanism serves to yieldingly control rotation of the table by steps.

Referring to Figure 7, reference numeral 58 designates heating apparatus, preferably a lead pot, for heating the projectiles. These are heated to a temperature above the transformation point, for example to 1500° F. to 1700° F. The work-

man, standing by the lead pot, lifts out a shot with his tongs and deposits it in the fixture 10 for the preliminary quench. The period of this quench is variable, but in the case of a 57 mm. shot, may be, for example, around 40 seconds. When this period is up, the workman lifts the shot from the fixture 10 and transfers it to the table of the secondary apparatus, at the same time giving the shot a push tangentially of the table so that the latter is advanced a step as controlled by the detent mechanism. The projectile eventually moves around to a workman standing at the end of a table 59 who lifts out the shot and deposits it on the table.

When the shot is removed and transferred to the rotary table its unquenched portion is still red hot, or substantially so, and the head may be at a temperature of around 150° F. During the secondary or head cooling operation, the heat from the unquenched portion begins to equalize throughout the shot insofar as it is able to. When the shot is removed from the rotary table, this equalization continues and is permitted to continue until complete. The shot is then permitted to cool to room temperature. The time the shot is in the rotary table at the secondary station is variable, but in the case of a 57 mm. shot may be several minutes, substantially longer than the initial quench. In the case of a shot of this size, equalization, after the secondary operation is completed, will take place in three or four minutes and the equalized temperature will ordinarily be around 325° F. to 350° F. The quenched portion of the shot is thus subjected to a drawing or tempering action so that stresses are relieved and a superior armor-piercing projectile is produced. Desirably the table 59 may be constituted by the upper run of a slow-moving conveyor of such length that heat-equalization will have been completed by the time the shot reaches the foot end of the conveyor.

It will be understood that variations under the invention are possible and are contemplated under the claims which follow. As stated at the outset, the method is useful wherever the differential quenching of oblong articles is to be accomplished, and the apparatus may, if necessary, be modified in accordance with the particular shape of the articles to be treated. In the case of articles of considerable length, it will only be necessary to heat a sufficient length at the end to be treated so that the heated but unquenched portion will supply sufficient heat to the quenched portion, upon equalization, to effect a drawing or tempering action.

I claim:

1. A quenching fixture for an oblong article of steel, comprising an upright bowl, means in the base portion of the bowl for supporting the article upright in the bowl, said bowl terminating upwardly below the upper end of the upright article and being of a capacity to provide flow clearance completely around the upright article, a horizontal collar supported in spaced relation to the upper edge of the bowl below the upper end of the supported article and having an opening of a size and so disposed as to receive the supported article with slight clearance, and an inlet in the bowl for a quenching fluid, whereby when fluid is flowed into the bowl it may escape both under and over said collar.
2. A fixture according to claim 1 wherein the collar is supported for vertical adjustment by pins extending upwardly from the bowl.
3. A quenching fixture for a steel projectile,

comprising an upright bowl, means in the base portion of the bowl for supporting the projectile head down in the bowl, said bowl terminating upwardly between the body ends of the supported projectile and being of a capacity to provide flow clearance completely around the projectile, a horizontal collar supported in spaced relation to the upper edge of the bowl with its top below the band seat of the projectile and having an opening of a size to receive the projectile body with slight clearance, and an inlet in the bowl for quenching fluid, whereby when fluid is flowed into the bowl it may escape both under and over said collar.
